UNITED STATES PATENT OFFICE.

LOUIS V. KUHN, OF COLUMBUS, OHIO, ASSIGNOR TO THE COLUMBUS VENDING COMPANY, OF COLUMBUS, OHIO, A CORPORATION OF OHIO.

VENDING-MACHINE.

1,245,928.

Specification of Letters Patent.

Patented Nov. 6, 1917.

Application filed June 18, 1915. Serial No. 34,923.

To all whom it may concern:

Be it known that I, LOUIS V. KUHN, a citizen of the United States, residing at Columbus, in the county of Franklin and State of Ohio, have invented certain new and useful Improvements in Vending-Machines, of which the following is a specification.

My invention relates to vending machines and has particular application to coin control mechanism of such nature whereby the insertion of a coin of predetermined value may be used as the means whereby the machine as a whole, may be operated.

The main object of my invention resides in a peculiar arrangement of locking bar and release bar for normally holding the machine as a whole in locked position, the locking bar itself being released by the action of a coin in connection with the release bar. In this manner a structure of very simple design and of comparatively low cost may be used to guard against the unauthorized manipulation of the machine when vending articles of the desired nature.

A further object of my invention resides in the provision of a structure to be used in combination with a plurality of operating members whereby only one of these operating members may be manipulated at any one time. In this connection it is to be understood that a plurality of operating members are provided whereby a machine may be built to vend different articles of the same or different values, the guard structure itself being provided to insure the owner that a customer will not obtain more than one article by one operation.

Further objects of my invention reside in the structure, more or less specific, as is shown in the accompanying sheets of drawings wherein similar characters of reference designate corresponding parts and wherein:

Figure 1 is a top plan view of the operating mechanism of my machine,

Fig. 2 is a bottom plan view of this operating mechanism,

Fig. 3 is a section taken on line 3-3 of Fig. 2 and looking in the direction of the arrows, and,

Fig. 4 is an enlarged section taken on line 4-4 of Fig. 1 looking in the direction of the arrows and with a portion of the framework removed.

In the drawings there is shown a main

body casting designated 1 mounted upon the base 2 by means of rivets or the like shown at 3. At one end of the machine and leading inwardly and downwardly from the front thereof, there is a coin chute 4 and mounted between the end pieces of the main body casting in a position directly beneath the coin chute, is the main frame plate 5. This frame plate slidably carries a plurality of slide operating members 6 on its upper surface, these operating members being cut out as is shown at 7 to form a dispensing pocket to coöperate with dispensing mechanism not shown in the drawings. Each of these slide members is also provided with a forwardly projecting tongue or lip 8, these portions 8 serving as hand grips for the convenient operation of the machine as a whole, after a coin has been placed in the coin chute 4. One longitudinal edge portion of each of the slide members is provided with a ledge such as is shown at 9, the portions 10 and 11 of these ledges being inclined to form a cam-way for purposes to be hereinafter described. The ledge along each longitudinal edge portion of each of the slide members, is also provided with a cut-out portion to form a shoulder such as is shown at 12, these shoulders being designed to normally maintain the machine in locked position by co-operation with a locking bar 13. It will be noted that this locking bar is of substantially U-shape, the leg portions 14 of the same being pivoted about a screw shown at 15. There is also provided a release bar designated 16, this release bar being similar in shape to the locking bar 13 and being similarly mounted, that is, mounted to pivot about its legs 17 and in the present instance about the same pivot screw 15 about which the locking bar 13 pivots. The locking bar 13 is normally forced to the position shown in Fig. 3, under the influence of the torsion spring 35, while the release bar maintains its position by gravity. This locking bar 13 is provided with a deflector finger shown at 18, this deflector finger projecting to a point directly adjacent the opening of the coin chute, in order that it may coöperate with the coin when the same is placed therein, as is shown in dotted outline in Fig. 3. From this figure and in connection with Fig. 1, it will be noted that the deflector finger 18 is so located and is of such width that it may engage the upper half of the coin when in 110

the position shown in Fig. 3. Further, this deflector finger is rigidly and adjustably mounted upon the locking bar by means of a slotted connection with its attaching screw 19, this adjustment being provided to adapt the machine to various sizes of coins as may be the desire of the owner. The release bar is provided with a forwardly projecting element 20, this element being provided with a laterally extending table portion 21. The projecting element 20 is rigidly mounted on one leg of a U-shaped release bar as is shown at 22 and the arrangement is such that the table portion projects directly beneath the open end of the coin chute 4 and is inclined slightly as is shown to prevent rearward movement of the coin when one of the slide members is operated.

The operation of the structure thus far described is as follows: A coin is placed in the coin chute 4 and because of its inclination, this coin will descend to assume the position shown in dotted outline in Fig. 3, in which position it rests upon the inclined table 21 carried by the forwardly projecting element 20. A pull on any one of the slide members 6 by grasping its forwardly projecting tongue 8, will bring its cam portion 10 into engagement with the release bar 16 and during the continued forward movement of the slide element, this release bar will be elevated. It will be noted that there is a certain amount of play or lost motion because of the cut-out portion forming the shoulder 12, but before the shoulder 12 has moved forwardly a distance sufficient to engage the locking bar 13 the inclined portion 10 will have elevated the release bar to such an extent that the forwardly projecting element 20 rigidly carried by it, will also have wedged the coin into engagement with the forwardly projecting finger 18 rigidly carried by the locking bar. This upward movement of the release bar is, therefore, communicated to the locking bar 13 and as a result, it will be elevated a distance sufficient to permit the passage of the slide plate forward without causing an engagement between the locking bar and the shoulder 12. In this manner, the machine is unlocked to permit its operation. Its operation thus far described, leaves both the table 21 and the finger 18 in contact with the coin and as a result, it cannot drop into the money drawer. As soon as the release bar 16 has reached the straight surface 23 between the camways 10 and 11, the locking bar 13 will have been brought into engagement with the camway 10 and consequently forward movement of the slide member will cause an additional elevation of this locking bar, which brings its finger 18 out of engagement with the upper half of the coin and because of the inclined

nature of the table 21, the coin will fall into 65 the money drawer by gravity.

Referring to Fig. 2 in particular, it will be noted that each of the slide members 6 is provided with a depending shoulder 24 on its underside, one edge of each shoulder being serrated as is shown at 25. These serrations are designed to coöperate with pawls 26 pivoted intermediate their ends, as is shown at 27 and normally held in the position shown in Fig. 2 by the coil springs 28. 75 Forward movement of the slide member 6 to bring the serrations 25 into engagement with the pawls 26 will slightly tilt the respective pawl against the tension of the spring 28 and as a result, rearward movement of the 80 slide member before it has completed its stroke to move the serrations beyond a position of engagement with the pawl 26, is prevented.

In order to guard against possibility of 85 more than one slide member being operated by the use of a single coin, I have provided a plurality of guard plates 29 as is shown particularly in Fig. 2, these guard plates being one less in number than the total 90 number of slide plates 6. These guard plates are mounted to move transversely to the path of movement of the slide plates by means of the pin and slot connection, such as is designated generally 95 at 30. It will also be noted that the rear edge of each of the guard plates has its corners cut away, as is shown at 31, to form inclines for coöperation with operating bolts 32 carried one to each of the slide members 100 6 and projecting through the slots 33 in the main frame plate. These operating bolts 32 are preferably carried at a point in the longitudinal center line of each of the slide members and the guard plates themselves 105 are of a width substantially equal in width to the slide members.

The operation of this portion of the mechanism is as follows: Referring particularly to the right of Fig. 2, forward movement of this slide member 6, it being assumed that a coin has been placed in the coin chute 4 and the release mechanism operating as has been already described, the operating bolt 32 will be brought into engagement with the incline 31 appearing to the right of the right hand guard plate 29. This incline causes the shifting of all of the guard plates to the left under the influence of the forward movement of the slide plate, by the engagement of the operating bolt 32. When these guard plates have been thus shifted, their relation is just the opposite from that as is shown in Fig. 2, and consequently it will be impossible for any one 120 of the other slide members to be moved forwardly, since there is not room sufficient to permit the spreading of the guard plates 125

for the entrance of a second operating bolt 32. This is true because these guard plates are of substantially the same width as the width of the slide members, or which corresponds to the distance between the operating bolts. However, as soon as the previously operated slide member is returned to normal position under the influence of its respective coil spring 34 any one of the other 10 of the slide members may be operated. Again assuming this structure to be in the position shown in Fig. 2, the operation of the second slide member from the right will cause a shifting of the first and second 15 guard plate 29 counted from the left, to the left and leave the third guard plate in the position it is shown. This movement of the two guard plates provides a path of a distance sufficient to accommodate the movement 20 of the corresponding operating bolt 32 before movement of any of the others is blocked.

From the foregoing description, taken in connection with the accompanying sheets of 25 drawings, it will be apparent that I have provided a comparatively simple type of vending machine wherein fraudulent operation is practically impossible. Also, the structure is very simple in its nature and 30 may, therefore, be produced at a comparatively small cost.

What I claim, is:

1. In a vending machine, a slide operating member formed with a camway and a 35 locking shoulder, a substantially U-shaped locking bar pivoted by its legs and arranged to coöperate with said shoulder, a substantially U-shaped release bar pivoted by its legs and arranged to coöperate with said 40 camway, a coin chute, a finger element rig-

idly carried by said locking bar and projecting to a point adjacent said chute to engage the upper half of a coin therein, and a table element rigidly carried by said release bar and projecting to a point adjacent 45 said chute to engage the under half of a coin therein, the arrangement being such that a pull on said slide member will elevate said locking bar through the elevation of said release bar caused by the release bar 50 engaging said camway.

2. In a vending machine, a plurality of slide operating members each formed with a camway and a locking shoulder, a substantially U-shaped locking bar pivoted by its 55 legs and arranged to coöperate with said shoulders, a substantially U-shaped release bar pivoted by its legs and arranged to coöperate with said camway, controlling means for said slide members whereby only 60 one of them may be in operation at any one time, a finger element rigidly carried by said locking bar and projecting to a point adjacent said chute to engage the upper half of a coin therein, and a table element 65 rigidly carried by said release bar and projecting to a point adjacent said chute to engage the under half of a coin therein, the arrangement being such that a pull on said slide member will elevate said locking bar 70 through the elevation of said release bar caused by the release bar engaging said camway.

In testimony whereof I affix my signature in presence of two witnesses.

LOUIS V. KUHN.
